UNITED STATES PATENT OFFICE.

GEORGE W. McGILL, OF NEW YORK, N. Y.

DESIGN FOR A SUSPENDING-BRACE FOR PICTURES.

Specification forming part of Design No. 6,323, dated December 24, 1872.

To all whom it may concern:

Be it known that I, GEORGE W. MCGILL, of the city and county of New York, in the State of New York, have invented a Design for a Suspending-Brace for Suspending and Bracing Pictures, Cards, &c., of which the following is a specification:

The nature of my design is fully represented in the accompanying drawing, to which reference is made.

The design is struck in one piece of metal, and consists of the brace A, provided with the raised ornamental border a a and ornamental garter D, as shown.

What I claim as my invention is—

The design for a suspending-brace for pictures, &c., as herein shown.

GEORGE W. MCGILL.
